UNITED STATES PATENT OFFICE.

JAMES STONE, OF AURORA, ASSIGNOR OF TWO-THIRDS TO ALICE M. BALL,
OF AURORA, AND ELIZABETH FLORSHEIM, OF CHICAGO, ILLINOIS.

COMBINED CORSET AND SKIRT-SUPPORTER.

SPECIFICATION forming part of Letters Patent No. 352,163, dated November 9, 1886.

Application filed October 26, 1885. Serial No. 180,900. (No model.)

To all whom it may concern:

Be it known that I, JAMES STONE, of Aurora, in the county of Kane and State of Illinois, have invented certain new and useful 5 Improvements in Skirt-Supporters for Corsets; and I do hereby declare that the following is a full, clear, and exact description thereof, reference being had to the accompanying drawings, and to the letters of reference marked 10 thereon, which form a part of this specification.

This invention relates to an improved skirt-supporter for corsets; and it consists in the matters hereinafter described, and pointed out 15 in the appended claims.

The dress-supporter herein shown as embodying my invention consists, principally, of one or more outwardly-curved and vertically-arranged metal springs attached at their ends 20 to the stiffening strips or busks of a corset by yielding connections, permitting the downward movement of the springs, as will hereinafter more fully appear.

In the accompanying drawings, illustrating 25 my invention, Figure 1 is a perspective view showing the rear part of a corset with skirt-supporting springs attached thereto. Fig. 2 is a detail sectional view of the same taken vertically through one of the stays or busks 30 and springs shown in Fig. 1. Figs. 3 and 4 are similar sectional views illustrating other ways of attaching the skirt-supporting springs.

In the said drawings, A indicates the body 35 of the corset, B the rear stays or busks, and C the skirt-supporting springs, which are secured to the busks below the waist-line of the corset. Said springs, as shown and preferably constructed, are of volute form in their upper part, and have their upper ends bent 40 inwardly and downwardly and their lower ends secured flat against the busks, thus giving a form of spring favorable for sustaining the garments, and at the same time capable of readily yielding to pressure.

45 A preferred construction in means for attaching the springs C to the stiffening strips or busks is shown in Figs. 1 and 2, in which the springs are connected at their upper ends with the lower ends of elastic straps D, secured to the corset at points above the springs,

whereby a downwardly-yielding connection is formed between the upper ends of the springs and the corset. Said straps D are, in the particular construction thereof herein illustrated, located against the outer faces of the busks B, 55 between the latter and the layer *a* of cloth covering said busks, and are secured to the cloth of the corset at the upper ends of the busks. In carrying out my invention, however, straps may be attached to the corset in other ways 60 than that shown, as may be found convenient or practicable, with essentially the same result.

The lower ends of the springs (shown in said Figs. 1 and 2) are provided with longitudinal 65 slots *c*, and are connected with the busks by headed studs *b* in the busks engaging said slots. This construction, obviously, allows the lower ends of the springs to yield downwardly when pressure is applied to said springs, tending to flatten them, as occurs when they are brought in contact with the back of a chair or seat, and also, in connection with the elastic straps D, enables the springs to yield bodily 70 downward to a limited extent, and thus yielding support the skirt in a manner tending to 75 promote the comfort of the wearer and to preserve a natural form in the dress.

As illustrated in Fig. 3, the spring C is held immovably at its upper end by means of an 80 eyelet passing through the spring and the busk B. The lower end of the spring is in this case slotted and held by a stud, *b*, as before described, so that the lower end of the spring will 85 yield downwardly when the pressure tending to depress or flatten it is applied thereto.

It is to be understood that the appended 90 claims cover the devices or parts therein set forth when said devices or parts are in form to obtain or perform either, any, or all of the advantages or functions obtained or performed by them in the particular form thereof illustrated.

I am aware that it has been proposed heretofore to employ, in connection with a corset, 95 skirt-supporters consisting of wire coils or rings connected with suspender-straps, which pass over the shoulders of the wearer by means of inelastic fabric strips passing through and sliding in vertical pockets formed in the body 100

of the corset, whereby the strain coming upon the coils or rings is taken by the shoulder-straps independently of the corset, while the pockets in the latter operate to hold the coils in proper position.

The construction herein claimed differs from that above referred to by having the bent metal springs by which the skirts are supported sustained from the corset-body and connected with 10 the latter by elastic connections, permitting a downward yielding of the springs, as hereinbefore fully set forth.

I claim as my invention—

1. The combination, with a corset, of a skirt- 15 supporter consisting of one or more outwardly bent or curved metal springs having sliding connection with the corset at their lower ends, and elastic connections uniting the upper ends of the said springs with the corset, substantially as described.

2. The combination, with a corset and the stiffening-strips thereof, of a skirt-supporter consisting of one or more bent metal springs provided with slots in their lower parts, said 25 strips being provided with headed studs engaging the slots, whereby a sliding connection

is formed between the lower parts of the springs and the corsets substantially as described.

3. The combination, with a corset, of a skirt- 30 supporter consisting of one or more springs movably connected at their ends with the corset, and elastic straps sustaining the springs, attached at their lower ends to the said springs and at their upper ends to the corset, substantially as described.

4. The combination, with a corset and the stiffening-strips thereof, of a skirt-supporter consisting of one or more curved springs provided in their lower parts with longitudinal 40 slots, headed studs upon the stiffening-strips engaging said slots, and elastic straps connecting the upper ends of the springs with the corset, substantially as described.

In testimony that I claim the foregoing as my 45 invention I affix my signature in presence of two witnesses.

JAMES STONE.

Witnesses:

C. CLARENCE POOLE,
M. E. DAYTON.
